UNITED STATES PATENT OFFICE.

ISAAC HIRSCH, OF CHICAGO, ILLINOIS.

TABLE-CUTLERY.

SPECIFICATION forming part of Letters Patent No. 783,785, dated February 28, 1905.

Application filed June 27, 1903. Serial No. 163,294.

To all whom it may concern:

Be it known that I, ISAAC HIRSCH, a citizen of the United States, residing at Chicago, in the county of Cook and State of Illinois, have 5 invented a new and useful Improvement in Table-Cutlery, of which the following is a specification.

My invention relates to improvements in table-cutlery, including knives and forks of 10 the class presenting a handle, bolster, and characteristic knife-blade or characteristic pronged portion, as the case may be. Table-cutlery with the aforesaid characteristics is standard; and my object is to provide certain 15 improvements therein with a view to cheapening the construction and rendering the finished article particularly strong, durable, and attractive.

In the drawings, Figure 1 is a finished article of table-cutlery made in accordance with 20 my improvements, showing the handle and knife-bolster, with a knife-blade, in full lines and a fork-substitute construction in dotted lines; Fig. 2, an enlarged broken view of the 25 knife construction, showing the handle and bolster portions in section; Figs. 3 and 4, side and end views, respectively, of a turned fork-bolster; and Figs. 5 and 6, similar views of the 30 same bolster pressed to render it oblong in cross-section. For a knife the bolster may be of the short form shown by full lines in Fig. 1 and have a slot *d* in its end to receive the butt-end of the knife-blade, as shown in Fig. 2. For a fork the bolster may be longer 35 to present the reduced neck portion *e*.

The characteristic knife-blade *A* or pronged fork-section, as the case may be, is stamped or otherwise formed out of a suitable metal and has an integral, preferably flat-sided, tang 40 *a*. The bolster *B* is turned in a lathe or screw-machine from preferably a steel rod-section or blank to a cylindrical shape, as illustrated in Figs. 3 and 4, to present any suitable ex-

ternal design. The bolster is formed with a central opening *b* and an annular flange *c* at 45 one end. After the bolster has been turned to shape it is preferably subjected to a squeezing operation in a suitable press to produce the oblong shape in cross-section shown in Figs. 5 and 6, thereby flattening the opening 50 *b*, whereby it will fit more or less snugly over the tang *a*. The bolster is applied to the tang preferably by driving it thereon, a little solder, if necessary, being applied between them to render the joint water-tight. The flange 55 *c* presents a surface to which a hollow handle *C* may be butt-welded. When the article is provided with a hollow handle, the tang *a* need be no longer than the bolster, as indicated by full lines in Fig. 2. When the article is provided with a mother-of-pearl or other 60 solid handle, the tang *a* should be of a length sufficient, as indicated by dotted lines in Fig. 2, to form, with the flange *c*, a means for fastening the solid handle securely in place. 65

The method of forming an article of table-cutlery by the process described presents advantages over all other processes of which I am aware, more especially in the matter of reducing the cost of manufacture, and the finished article is particularly strong and durable in every way. When finished, the article has all the appearance of having been forged 70 in one piece.

What I claim as new, and desire to secure 75 by Letters Patent, is—

An article of table-cutlery which consists of a blade or prong portion having an integral flat-sided tang, a turned and flattened bolster having a central opening fitting tightly the 80 flat-sided tang, and an independently-formed handle secured to the bolster.

ISAAC HIRSCH.
